UNITED STATES PATENT OFFICE.

FRANK ISELE, OF CHICAGO, ILLINOIS.

NOSE-BAG.

1,296,962.

Specification of Letters Patent. Patented Mar. 11, 1919.

Application filed September 21, 1918. Serial No. 255,100.

To all whom it may concern:

Be it known that I, FRANK ISELE, a citizen of the United States, residing at Chicago, in the county of Cook, and State of Illinois, 5 have invented new and useful Improvements in Nose-Bags, of which the following is a specification.

This invention relates to feeding devices for animals, particularly to nose bags, and 10 has for its object the provision of a nose bag supported from head engaging straps by means of a pair of springs disposed at each side of the bag and of such tensional resistance that the weight of the bag when full of 15 feed will extend the springs so that the upper surface of the body of feed within the bag will be disposed conveniently at the mouth of the animal, the tension of the springs automatically raising the bag as the 20 feed therein is consumed.

An important object is the provision of a nose bag of this character which is so formed that it may be adjusted for use upon animals having short or long heads.

25 A further object is the provision of a nose bag of this character which will be extremely simple and inexpensive in manufacture, highly efficient and durable in use, easily applied, efficient in operation and a 30 general improvement of the art.

With the above and other objects and advantages in view, the invention consists in the details of construction to be hereinafter more fully described and claimed and illustrated in the accompanying drawings in 35 which:

Figure 1 as a side elevation of my novel nose bag in position upon the head of a horse and

40 Fig. 2 is a front elevation thereof detached.

Referring more particularly to the drawing, the numeral 5 designates a feed bag which may be of any well known or preferred construction, and the numeral 6 designates a strap engageable over the head of the animal. If desired, the strap may have secured thereto a forehead engaging strap 7 and a throat encircling strap 8 provided with 45 a suitable snap hook 9 engageable with a ring 10 whereby the bag may be suitably secured upon the head of the animal.

50 In carrying out my invention I provide a

novel connection between the upper edge of the bag 5 and the lower ends of the strap 6. 55 This connection comprises a spring 11 disposed upon each side of the feed bag at diametrically opposite points. Each spring 11 has one terminal passed through a loop 12 formed on the upper end of a strap or 60 tab 13 secured upon the feed bag and has its other terminal passed through a loop 14 which carries a buckle 15 engageable with one end of the head encircling strap 6 and adjustably connected therewith by means of 65 engagement of the buckle tongue within a selected one of openings 16 in the strap 6.

It will thus be seen that the feed bag 5 is entirely supported from the head engaging strap by means of the springs 11. The 70 springs 11 are formed of wire of such resilience that when the feed bag is full the weight thereof will extend the springs 11 downwardly so that the surface of the body of feed contained within the bag 5 will be 75 disposed adjacent the mouth of the animal. It will of course be apparent that as the feed is consumed the tension of the springs will raise the bag 5 so that the surface of the feed therein will always be held in the same relative position in respect to the mouth of the 80 animal.

In order to prevent any possible chafing of the animal by the springs 11, I preferably provide flaps 17 secured adjacent the lower 85 ends of the straps 6 and disposed between the springs 11 and the side of the animal's head. These flaps 17 must be of sufficient length as to protect the animal when the springs are extended to their maximum extent. 90

From the foregoing description and a study of the drawings it will be apparent that I have thus provided a peculiarly constructed nose bag which may be quickly and 95 easily placed in position upon the head of an animal and which will be automatically regulated by the weight of feed within the bag so that the feed will be conveniently positioned at the mouth of the animal to facilitate feeding. 100

What is claimed is:

A device of the character described comprising a bag, a head engaging strap, a pair of springs connected with the upper edge of 105 said bag at diametrically opposite points,

and a flap secured at each end of said strap and disposed against the inner side of the associated spring, said flaps being of a length equal to the length of said springs when said springs are extended to their maximum length, the lower ends of said straps being free and slideable with respect

to the bag whereby they will remain interposed between the springs and the head of the animal to which the bag is applied irrespective of the degree of extension or retraction of said springs.

In testimony whereof I affix my signature.

FRANK ISELE.
